FIG. 1

FIG. 2

FIG. 3

FIG. 4

FIGURE 1 is a front elevational view of a mobile brush burner unit for delivering air and fuel to facilitate and maintain brush fires and the like embodying my new design;

FIGURE 2 is a side elevational view of the mobile brush burner unit for delivering air and fuel to facilitate and maintain brush fires and the like, the opposite side thereof being substantially the same in appearance;

FIGURE 3 is a top plan view; and

FIGURE 4 is a rear elevational view.

The hose member is shown broken away in part in FIGS. 1, 2, 3, and 4 to indicate indeterminate length.

I claim:

The ornamental design for a mobile brush burner unit for delivering air and fuel to facilitate and maintain brush fires and the like, as shown and described.
